UNITED STATES PATENT OFFICE.

FRANCIS JOHN MARONKA, OF CHICAGO, ILLINOIS.

MONOPLANE.

1,167,581.

Specification of Letters Patent. Patented Jan. 11, 1916.

Application filed April 26, 1913. Serial No. 763,716.

To all whom it may concern:

Be it known that I, FRANCIS JOHN MARONKA, a subject of Russia, and resident of Chicago, in the county of Cook and State 5 of Illinois, have invented certain new and useful Improvements in Monoplanes, of which the following is a full, clear, and exact specification.

This invention relates to improvements in 10 monoplanes in which heretofore the propellers are at the forward end of the machine, and have required a rudder manipulated by the operator for steering purposes.

The prime object of my invention is a 15 monoplane in which the seat of the occupant is at the center of gravity thereof, and by which it is made possible and practical to steer the machine solely through the shifting of the center of gravity of the occupant, 20 as by bending the body in the direction he desires to have the machine take.

A further object of my invention is a 25 monoplane the propellers of which are located at the rear end of the machine.

More specifically stated the object of my 30 invention is a monoplane, the body of which in its entirety in angles and curves transversely and longitudinally conforms substantially and as nearly as may be to those of 35 the body of a bird when its wings are outstretched, and in which the center of its gravity when flying and the body of the occupant is in an upright position, is through the vertical center of the operator whereby 40 the operator by shifting the center of gravity of his body is enabled to control his direction of flight, and without other means steer the monoplane in the direction he wishes it to take.

With these ends in view, my invention finds 45 embodiment in certain features of novelty in the construction, combination and arrangement of parts by which the said objects and certain other objects are herein attained, all as fully described with reference to the accompanying drawings, and more particularly pointed out in the 50 claims.

In said drawings: Figure 1 illustrates a top 55 plan view of a monoplane in which my invention finds embodiment. Fig. 2 is a side elevation thereof. Fig. 3 is a transverse section on the line 3—3 of Fig. 2. Fig. 4 is

a transverse section on the line 4—4 of Fig. 2, and Figs. 5, 6 and 7 are a transverse section on the line 5—5 of Fig. 2. Fig. 8 is a view of the landing wheels.

Similar characters of reference indicate the same parts in the several figures of the drawings.

For convenience of description, the monoplane of my invention will be referred to as consisting of the body portion 8, and beak 9, which however constructed are integrally jointed, especially when made up of thin sheets of aluminum, which they preferably are, but may be of board, paper or wood, forming a thin but very strong and shell like structure. The body portion 8 consists of straight sides 10—10 substantially parallel, 65 but may taper from their forward toward their rear ends, and connected by a bottom 11 struck on a downwardly projecting curve, the trough like structure thus formed being closed at its rear end as indicated at 12. 70 With reference to a horizontal plane the lower edges of the side pieces 10—10 are parallel therewith, with their upper edges slightly inclining upwardly from their rear to their forward ends, so that in effect an 75 upward pitch is given to the wings 13 and 14 supported on top of the sides 10—10, and to which they are secured by any means, or in any manner suitable to that end. The beak 9 integral, or otherwise rigidly secured 80 to the front end of the body portion 8 is substantially triangular in cross-section throughout its length, arranged with its apex or upper edge 15 preferably in a plane substantially above that of the body portion. 85 The opposing sides 16 and 17 of the beak converge along with their meeting edges at the bottom 18 of the beak to a point 19, or in other words the bottom edges of the 90 opposing sides 16 and 17 having a graduated pitch from the body portion to the forward termination of their upper edges, first from the body portion upon a line 20 pitching upwardly from the plane of the bottom of the body portion, thence along a line 21 of 95 shorter angle forwardly to a point 22 and thence along an upwardly curved line 23 to the apex and upper edge 15 of the beak. The side pieces 16 and 17 of the beak from about the dotted line 5—5 to the body are 100 convexed outwardly, but from this line 105

5—5 to the beak the sides 16 and 17 are preferably concaved toward each other, but may be in straight lines. The piece forming the inclosing bottom of this shell like beak 5 is convexed as indicated at 24, which convexity adjacent the body 8 conforms thereto but gradually decreases to the point indicated at 25 from which point to the beak the surface of the bottom is flat, but if desired 10 may be slightly concave.

It will now be observed that wings 13 and 14 are each substantially the same width, but that the wings 14 are much longer than the wings 13, and extending across the body 15 portion, serve to form a cover for the length of the body portion corresponding with their width, and which wings 13 do not, and therefore between which latter wings is an opening 20 to a pit 26 in the body for occupancy by the operator of the machine upon a seat 27, located at the center of gravity of the monoplane. For convenience of construction the wings 13 and 14 may be made in one piece, and while the shorter wings 13 25 are shown rounded on their ends, these ends may diverge from their front along straight lines to the outer ends of the wings 14 as will be understood by bearing in mind that the object of having the forward end of these wings as a whole shorter than the 30 length of their rear edges is to facilitate the cutting of the air, and the buoyancy of the monoplane, and its steering by having a greater area of rear than forward wing 35 surface for the displacement of the air currents pressing upwardly against the wing surface, and in short promoting a pivotal action to the monoplane for making turns.

As a means for propelling the monoplane, it is to be provided with a suitable gas engine indicated by dotted lines at 28, power shaft 29 of which is provided with suitable bearings (not shown) and projecting through the end 12 of the body portion 40 45 has secured thereto wings 30—30 constituting a propeller for the machine pushing the machine forward instead of pulling it forward as in monoplanes heretofore, in which the propeller is in the front end thereof.

The location of the propeller at the rear 50 instead of the forward end of a monoplane is regarded, and no doubt is of great advantage in several respects, among which may be mentioned that the operator has a better and more perfect control over his machine for steering purposes when steering a monoplane by shifting the center of gravity of his body as is contemplated by my invention; that a pushing force by propellers will produce a higher rate of speed with 55 the same power than is possible by a pulling force, such as heretofore has been commonly employed for the propulsion of monoplanes, and as must be with their propellers 60 in front, and which when so located not

only tend to obscure the view of the operator in steering, produce an objectionable noise and moreover are not only liable to, but frequently have injured the occupant owing to their striking him if he pitches 70 forward but slightly, or from a splinter therefrom, and when with the propellers at the rear of the machine he would be perfectly secure from any such injury.

As a desirable means for facilitating the 75 starting and landing of my monoplane, it has secured thereto, the ends of bent rods or V-shaped bars 31, forming a support and stop for the opposite ends of the axle 32 rotatable on which are wheels 33. Riveted 80 or otherwise secured on top of the axle is a bent bar 34, the ends of which are bent upwardly and perforated to form bearings for rods 35, secured at their upper ends to the body of the monoplane, and projecting 85 through perforations in the bracket, the axle and the apex of the V-shaped bars 31, and whereby the axle is slideable on said rods. Coiled about these rods with an end bearing against the body of the monoplane, and the end bracket 34 are springs 36, below which, and abutting against the underside of the bracket and against the axle are other springs 37 for absorbing shocks, otherwise imparted to the monoplane and its 90 occupant when the wheels come in contact with the ground. In other words both the front and rear axles and wheels are spring seated by one set of springs, and their tendency to rise resisted by opposing springs, the effect of which is to not only give the 95 wheels great resiliency when rolling on the ground, but also when striking the ground on the descent of the machine, both of which results are accomplished by very simple, effective and durable devices.

In the operation of my monoplane it will now be seen that when making a ground start the occupant by swaying his body 100 backwardly from an upright position shifts the center of gravity toward the rear end of the machine, with the result that the beak of the machine is lifted so to speak, and pointed upwardly at any desired angle by the occupant, depending upon how far he 105 may lean his body toward the rear end of the machine, and if on the other hand, he desires to descend from a height he has but to lean forward to depress the beak of his machine, and at whatever angle he may desire, depending upon how far he leans forward and correspondingly shifts the center of gravity toward the front end of the machine. It will now be observed that with 110 proper balance on the part of the operator the curved bottom of the body, and of the beak will displace the air uniformly at both sides thereof, while the flattened portion of the beak receiving the force of the current of air at a right angle thereto offers 115 120 125 130

such a resistance that the operator may steer the machine downwardly at whatever angle he may desire, and that on the other hand if he desires before reaching the ground to 5 reascend he has but to move his body in a straight line backward to an upright position in line with the center of gravity through his body, and the machine, when it will assume and move forward in a horizontal position, or he may in the first instance when 10 he desires to reascend while in the air gradually shift his body until its gravity has been shifted past normal toward the rear of the machine, and when the monoplane 15 will reascend. When the monoplane is flying horizontally in mid air and the occupant wishes to steer the machine to the left, he inclines his body from an upright position sidewise to the left, and when under the 20 same plane of flight he desires to steer the monoplane to the right he likewise inclines his body from an upright position to the right of him, but if he wishes to make either of these turns when flying either in an up- 25 ward or downward direction, he leans to the right or left with his body inclined forward or backward as may be, while steering the monoplane and regulating his propeller as may seem best by means (not shown) 30 within his reach for controlling the engine to conform thereto. When the occupant leans to the left for making a turn in that direction, and the monoplane is so turning, it will now be seen by reference to Fig. 5 35 that the impact of the air against the under- side of the wings and the straight sides of the body, and the concaved side of the beak at his right will be increased, while on the other hand, the pressure of the air against 40 the corresponding surfaces on his left will be decreased to whatever extent he shifts the center of gravity of the machine in that direction. The tilting of the machine is made easier and quicker responsive to the 45 shifting of the center of gravity as above described by reason of the convexed surface of the bottom of the body, and that of the rear end of the beak. It will now be ob- 50 served that owing to the tapered and pointed form of the beak it not only facilitates the penetration of the air by the monoplane, but responds to the shifted gravity for pointing in the desired direction.

A storage tank (not shown) for liquid 55 fuel, such for example, as gasoline may and should be so arranged that its center of gravity shall be on the same line as that of the operator when sitting in an upright position, and to this end may be directly beneath his seat, and may extend into the beak, or on the other hand, the beak itself may be utilized as a storage tank, and its center of gravity be maintained by a shifting 60 weight as the weight of the gasoline is de- creased from consumption, which weight

may be hand operated, but preferably automatically by the employment of a float or floats in the receptacle.

In order to maintain the point of center of gravity fixed so that it may be substantially unchangeable by the shifting of the gasoline in the receptacle from front to rear or from side to side both when the machine is ascending and descending, it is the intention to employ partitions in the receptacle 70 so dividing the body of gasoline that the center of gravity of the gasoline may be maintained substantially at a fixed and predetermined point, and as may be by partitions set at such angles that the gasoline for 75 example, will be divided into two bodies having a wedge-like form with the apex of one wedge projecting to the base of the other wedge.

My invention includes broadly any form 80 or construction of monoplane, the center of gravity of which is so located that it may be shifted by the shifting of the center of gravity of the occupant, and thereby permit him to control the steering of the machine 85 in any necessary or desired direction, and is therefore, not limited to any special means for maintaining the center of gravity of a liquid fuel, especially when it is seemingly now possible and practical to employ elec- 90 tricity as a motor power, the center of gravity of which is stable when once fixed.

Having described my invention, what I desire to secure by Letters Patent is:

1. A monoplane comprising in combina- 100 tion a body portion, having parallel sides and a convex bottom, a beak-like member projecting forwardly thereof, in cross section substantially triangular.

2. A monoplane comprising in combina- 105 tion a body portion, the sides of which are parallel, and its bottom convex, a beak-like member at the forward end thereof, the bottom of which adjacent the body is convexed, and gradually merges into a substantially 110 flat transverse surface to the point of the beak, substantially as described.

3. A monoplane comprising in combina- 115 tion a body portion the side walls of which increase in width from the rear toward their front ends, a convexed bottom connecting said side walls, a beak like portion at the forward end thereof, the bottom of which converges to a point and extends upwardly at an angle from the body portion, 120 substantially as described.

4. A monoplane comprising in combina- 125 tion a body portion, the outer side faces of which are parallel, a beak-like portion projecting from the forward end thereof, triangular in cross-section with its several sides converging to a point terminating at the apex of the beak-like portion.

5. A monoplane comprising in combina- 130 tion a body portion, the opposing side faces

of which extend in parallel lines and increase in width from rear to front, a beak-like portion joined to the forward end thereof, triangular in cross-section and converging to a point adjacent which the bottom curves upwardly.

In witness whereof, I have hereunto set

my hand and affixed my seal this 15th day
of April A. D. 1913.

FRANCIS JOHN MARONKA. [S.]
